CHARLES A. UPSON, OF LOCKPORT, NEW YORK, ASSIGNOR TO THE UPSON COMPANY, OF LOCKPORT, NEW YORK, A CORPORATION OF NEW YORK

EMBOSSING WALL BOARD

Application filed February 23, 1928. Serial No. 256,348.

My present invention relates to the manufacture of wallboard and similar material as used in building construction, and for decorative purposes. More particularly it relates to the manufacture of a wallboard of this character that is of substantial thickness, and is made up of a body or core of one material and facings or "liners" as they are called of another material applied to one or both 5 faces of the core. The invention has for its principal object to provide a simple, convenient and effective method of producing such a wall board with an embossed face or outer surface carrying a selected design, as for 10 instance, an imitation of brick work or tiling. The invention contemplates the process applicable where the nature of the board to be produced is such that it works against ordinary embossing methods, either because 15 the latter would impair the texture of the board, or would be ineffective to produce the 20 clear and satisfactory embossing effect.

To these and other ends the invention resides in certain improvements and combinations of parts, all as will be hereinafter more fully described, the novel features being pointed out in the claims at the end of the specification.

In the drawings:

Fig. 1 is a side view partly in vertical section of the feed end of a wallboard making machine of a nature adaptable to the practice of my invention;

Fig. 2 is an enlarged elevation of an embossing roll that may be used;

Fig. 3 is an enlarged fragmentary section through a wallboard product made in accordance with my invention; and

Fig. 4 is a plan view of the embossed face 40 of the product.

Similar reference numerals throughout the several views indicate the same parts.

Referring first to Fig. 3 wherein is shown a preferred construction of wallboard suitable for manufacture in accordance with my improved method, this board indicated generally at A consists of two heavy paper liners B and C adhesively secured to the opposite side of an intermediate core or body portion D. By "adhesively secured" I do not

mean necessarily that a third separate adhesive element is used for, in the present instance the body is itself adhesive in character, and attaches itself tenaciously to the inner surfaces of the liners.

It has been discovered that when a mixture of sodium silicate solution and powdered dolomite in approximate proportions of two-parts silicate to three-parts dolomite is made into a batch with sixteen or seventeen percent of water it possesses intumescent qualities, and when subjected, in a confined state, to heat of from 225 to 300° F. the mass will puff and become cellular during the escape of the moisture content in the form of steam. The water escapes rapidly, particularly in the thin sheets or bodies used in wallboard, and with its escape, particularly after a further hardening or curing heat treatment, the resulting product is a hard stiff 60 cellular body of a moderate frangibility commensurate with its stiffness. Such a body is the core D of the product herein shown.

In the manufacture of such a board the batch above described is introduced as a 75 plastic mass between the two paper liner strips B and C which accompany it into an intumescent chamber where, during the intumescent action the core becomes adhesively 80 fixed to the faces of the liners forming a homogeneous structure. This is preferably carried on as a continuous process as herein-after described.

It is impracticable to emboss by the ordinary method of pressure rolls the completed 85 article described for the reason that the necessary pressure to effect a clear design is apt to either impair the texture of the core body D or warp and deform the board as a whole.

In the practice of my invention I avoid these difficulties by first embossing, by means of pressure rolls or otherwise, the liner that is to become the finished face of the board 95 by itself before associating it with the core body and companion liner. I then apply the inorganic filler in the plastic state, together with the other liner (if used) and immediately subject this structure to the moderately high degree of heat aforesaid which quickly 100

drives off the moisture content, the same escaping at the edges of the board. With the materials suggested this can be accomplished by a travel of from fifty to one hundred feet 5 through heated platens at the temperature given and at the rate of twenty feet per minute. Due to the relatively small amount of moisture or water present in this inorganic core mass and the rapidity with which it is 10 discharged, the paper liners are not impregnated therewith, and the embossed liner C is therefore not softened sufficiently to impair the distinctness and permanency of the embossed effect. In fact, there is greater danger 15 of overheating the paper liner to a degree that renders its surface brittle by baking out the surface fibres.

Referring again to the drawings, I have 20 illustrated therein the general arrangement of a machine for carrying out my method. In Fig. 1, 1 indicates a suitably mounted paper supply roll on an axle 2 for furnishing the inside liner B which passes beneath a guide roll 3 and over a driven feed roll 4 beneath a hopper 5. The front or facing liner C is brought from a roll 6 on an axle 7 around guide rolls 8 and 9 and over a driven feed roll 10 beneath the hopper 5. The feed rolls 4 and 10 are mates as shown, turning in opposite 25 directions and bringing the liner strips into suitable parallel proximity. It is at this point that the batch 11 that is to constitute the core is introduced between them from the hopper 5. The material is then passed as a composite 30 body A' between upper heated platens 12 and lower heated platens 13 on a heating bed 14. The platens may be suitably steam heated and are open at the sides of the machine to permit the escape of steam as aforesaid.

40 The liner C may be embossed before being wound into the roll 6, but I prefer at present to emboss it after it leaves the roll on its way to hopper 5 containing the plastic. For this purpose I provide at this point an embossing couple composed of an upper suitably driven embossing roll 15 and a lower companion platen roll 16. A typical embossing roll is shown in Fig. 2 designed to make longitudinal and transverse scores or depressed 45 imprints upon the face of the paper in simulation of tiling, such as is used in bath rooms and kitchens. When enameled a board so embossed and constructed as described gives a very real effect in both surface appearance 50 and stability. It is obvious that the reverse or inside liner B may be omitted.

I claim:

1. The method of producing embossed wallboard embodying a flexible liner and a 60 body of inorganic filler adhesively attached thereto which comprises first embossing the liner on one surface only under pressure, the other surface remaining smooth, applying the filler to the smooth side thereof in a plastic state and then subjecting the struc-

ture immediately to a relatively high degree of heat to drive the moisture from the filler before the liner is impregnated therewith while at the same time supporting the liner side of the structure continuously against a 70 smooth flat surface.

2. The method of producing embossed wallboard embodying a pair of liners of fibrous material and a filler of inorganic material between them, which comprises first 75 embossing one of said liners along a plurality of lines at an angle to each other, applying the filler between said liners in a plastic state and with a relatively low moisture content, and then subjecting the filler and liners substantially immediately to relatively high heat to drive moisture from the filler before the embossed liner becomes impregnated with moisture and softened.

3. The method of producing embossed wallboard embodying a pair of liners of fibrous material and an intumescent filler between said liners of sodium silicate and mineral matter, which comprises first embossing one of said liners along a plurality of lines 80 at an angle to each other, applying the filler between said liners in a plastic state and with a relatively low moisture content, and then subjecting the filler and liners substantially 85 immediately to relatively high heat to cause 90 said filler to intumesce and to drive moisture from the filler in the form of steam before the embossed liner becomes impregnated with moisture and softened.
